UNITED STATES PATENT OFFICE.

JOHN ERNEST DUNWOODY, OF BELFAST, IRELAND.

LOADING OF MAGAZINE-DRUMS OF LEWIS AND LIKE GUNS.

1,306,416.

Specification of Letters Patent. Patented June 10, 1919.

Application filed January 23, 1918. Serial No. 213,285.

To all whom it may concern:

Be it known that I, JOHN ERNEST DUNWOODY, of 92 Holywood road, Strandtown, Belfast, Ireland, a subject of the King of Great Britain and Ireland, have invented certain new and useful Improvements Relating to the Loading of Magazine-Drums of Lewis and like Guns, of which the following is a specification.

10 This invention relates to guns and rifles of the class having a removable circular drum magazine, (such, for instance as the "Lewis" gun) and its object is to provide a convenient and easily portable device adapted to effect the rapid loading of the magazine drums. At present the drums are generally filled or loaded by hand, one cartridge at a time, and on an average, about 15 ninety seconds are required to fill a single 20 drum whereas, with my device, a drum can be filled with cartridges in fifteen seconds.

The filling or loading device comprises a suitably shaped receptacle for one or more cartridge clips with cartridges therein, and, 25 working through a slot in the bottom of the clip receptacle, is a member connected with a hand lever which is pivotally connected with the frame of the device in such manner that movements of the hand lever in one 30 direction will cause the member, connected therewith, to engage or press on the cartridges in the clip, or in the lowest clip when more than one clip is in the receptacle, and force them out of the clip into an inclined 35 chute, while, at the same time, the member will engage itself with the springs of the clip so that when the member is moved back by the hand lever to its starting position it will, during such movement, carry away or 40 eject the empty clip and so allow the next clip to drop into position. The cartridges delivered from the clip into the inclined chute roll down same and fall, one at a time, into position in the magazine drum which is 45 removably and turnably supported underneath and correspondingly and suitably turned through the medium of a hand lever and simultaneously with the delivery of the cartridges from the clip, so that each cartridge falls from the chute into its proper 50 position in the drum, means being provided to prevent the drum turning back to the starting position, said means being capable

of allowing the reversal of the drum when necessary.

In order that the invention may be clearly understood I have hereunto appended explanatory drawings, whereon:—

Figure 1 is a side elevation of the device. 55

Fig. 2 is a plan view of the same. 60

Fig. 3 is another side elevation with parts cut away to show how the cartridges are delivered into the chute and from the chute to the drum.

Fig. 4 is an isometric view with parts cut away to show the automatic stop. 65

Referring to the drawings:—

The filling or loading device comprises a receptacle *a* supported on a frame *e* having at its underside a magazine post or spindle *e*¹ for the magazine drum *g* and whereon the drum is turnable. The receptacle *a* is shaped to receive the full cartridge clips *b*. In the bottom of the receptacle *a* is a slot *a*¹ (see Fig. 2) and, at one side, an opening leads to an inclined chute *f*, another opening being provided at the opposite side of the receptacle so that a member *c*, working through the slot *a*¹ and connected with a hand lever *d* pivotally connected with the frame *e* at *e*², can be moved into the receptacle and out of same again in such manner that movements of the hand lever *d* in the direction of the arrow *x* (Fig. 2) will cause the member *c* to press the cartridges *b*¹ out of the clip *b* at the bottom of the receptacle, or out of the lowest clip if more than one clip is in the receptacle *a*. The cartridges are forced out of the clip by the member *c* and they are pushed through the opening in the side of the receptacle so that they fall down the inclined chute *f* while, at the same time, a spring catch *c*¹ on the member *c* engages the clip *b* in such manner that when the member *c* is moved back, by the moving back of the hand lever to its starting point, it will, during such movement, carry away, or eject, the empty clip through the opening at the opposite side of the receptacle and allow the next full clip to fall into position. 75 The lower end *f*¹ of the chute *f* is so positioned relatively to the cartridge spaces of the drum that a cartridge falling therefrom will drop into proper position with its nose end between the separating or space pins *g*¹ 80 and its back end engaging in the correspond- 90 95 100 105

ing recess g^2 , the proper positioning of the cartridge, leaving the chute being further insured by the supporting tongue h (Fig. 3) which holds up the back end of the cartridge 5 until the usual top ring or plate g^3 covers the nose of the cartridge and prevents it rising out of position.

The turning of the drum g to correspond with the discharge of the cartridges from the chute f is effected by a lever arm k having its one end k^1 turnably fitted above the magazine post or spindle e^1 and concentric therewith, and, its other end k^2 , which has a portion k^3 extending down out- 10 side of the drum, provided with a spring catch k^4 , or equivalent, adapted to engage the recesses g^4 in the periphery of the drum. On the turning of the hand lever d to empty the cartridges from the clip b into the inclined chute f , a connection, or link l , between the arm d^1 of the hand lever d and the drum operating lever arm k causes the latter, through the medium of the spring catch k^4 , to correspondingly move 15 and turn the drum in such manner that the cartridges fall into position therein. The spring catch k^4 is so made that during the reverse, or backward movement, of the lever arm k the drum g is not moved, so that, 20 in effect, the drum g is given an intermittent movement always in one direction only, and corresponding to the discharge of cartridges b^1 from the clips b into the inclined chute f . Preferably, one movement of the 25 hand lever empties a clip into the chute and effects such corresponding turning movement of the drum g as allows of the cartridges being properly positioned in the drum. The return movement of the hand lever is effected, or assisted, by a spring m pulled into tension during the forward movement of the hand lever. The device 30 may be supported on a tripod, or, as in the example shown, it may be provided with a depending arm n^1 with a spike n to stick in the ground and a clamp o to fit on the side of a cartridge box.

In order to automatically stop the action of the device if, and when, a cartridge fails 35 to reach its proper position so that a blank space would result, I provide a disk p^1 on a rod p connected with a lever member q fulcrumed at q^1 and having at its end q^2 a number of notches q^3 . The disk p^1 rests 40 on the cartridges in the drum and, normally, it is so held up thereby that the end q^2 is kept clear of the lever arm d^1 . Should the disk encounter a blank space it immediately falls and brings down the end q^2 45 so that the notches q^3 therein engage the lever d^1 and prevent the further filling of the drum which can then be reversed by pulling out the catch k^4 and turning back the drum g until the empty space has been

filled when the filling operation can again 65 proceed.

When a drum has been filled and some cartridges remain in the chute f they may be held up by the disk p^1 and so be ready for the next drum to be filled and also permit it being positioned without difficulty. 70

By the use of a device such as above described one man can fill six drums in the time usually taken to fill one so that a very great saving in time and labor is effected. 75

Having now fully described my invention what I claim and desire to secure by Letters Patent is:—

1. A loading device for the magazine drums of "Lewis" and like machine guns, 80 comprising, in combination, a receptacle for cartridges in clips, a frame carrying the receptacle, means on the frame about which the drum can turn, a member capable of being projected into the receptacle to force 85 the cartridges from the clips and feed them to the drum, and a lever for actuating the said member and also at the same time turning the drum.

2. A loading device for the magazine 90 drums of "Lewis" and like machine guns, comprising, in combination, a cartridge receptacle with inclined chute for delivering the cartridges to the drum, a frame carrying the receptacle, means on the frame about 95 which the drum can turn, a member capable of being projected into the receptacle to feed the cartridges to the drum, and a lever for actuating the said member and also at the same time turning the drum. 100

3. A loading device for the magazine drums of "Lewis" and like machine guns, comprising, in combination, a frame adapted to fit on the magazine drum, a center on the frame about which the drum can be 105 turned, a receptacle on the frame for the reception of cartridges in clips, a lever pivoted on the frame and connectible with the drum to turn the same and means operated by the lever for discharging the cartridges 110 from the clips.

4. A loading device for the magazine drums of "Lewis" and like machine guns, comprising, in combination, a frame adapted to fit on the magazine drum, a center on the 115 frame about which the drum can be turned, a receptacle on the frame for the reception of cartridges in clips, a lever pivoted on the frame and connectible with the drum to turn the same and means operated by the lever for discharging the cartridges from 120 the clips and for ejecting the clips.

5. A loading device for the magazine drums of "Lewis" and like machine guns, comprising, in combination, a frame adapted 125 to fit on the magazine drum, a center on the frame about which the drum can be turned, a receptacle on the frame for the re-

ception of cartridges in clips, a lever pivoted on the frame and connectible with the drum to turn the same and means operated by the lever for discharging the cartridges 5 from the clips when operated in one direction and of ejecting the clips when operated in the opposite direction.

6. A loading device for the magazine drums of "Lewis" and like machine guns, 10 comprising, in combination, a frame adapted to fit on the magazine drum, a center on the frame about which the drum can be turned, a receptacle on the frame for the reception of cartridges in clips, a lever pivoted on the 15 frame and connectible with the drum to turn the same and means operated by the lever for discharging the cartridges from the clips to an inclined chute leading from the receptacle to the drum and adapted to 20 feed the cartridges thereto.

7. A loading device for the magazine drums of "Lewis" and like machine guns, 25 comprising, in combination, a frame adapted to fit on the magazine drum, a center on the frame about which the drum can be turned, a receptacle on the frame for the reception of cartridges in clips, a lever pivoted on the

frame and connectible with the drum to turn the same, means operated by the lever for discharging the cartridges from the 30 clips and means for automatically arresting the feed when a cartridge fails to reach its proper position in the drum.

8. A loading device for the magazine drums of "Lewis" and like machine guns, 35 comprising, in combination, a frame adapted to fit on the magazine drum, a center on the frame about which the drum can be turned, a receptacle on the frame for the reception of cartridges in clips, a lever pivoted on the 40 frame and connectible with the drum to turn the same, means operated by the lever for discharging the cartridges from the clips and a pivotal lever catch with stop for automatically arresting the feed when a 45 cartridge fails to reach its proper position in the drum.

In testimony whereof I affix my signature in presence of two witnesses.

JOHN ERNEST DUNWOODY.
